The present invention relates to protective devices for preventing loss of purses from pockets of articles of clothing, such as trouser pockets, and is particularly concerned with a simple, practical and inexpensive device which may be removably engaged with a purse. As used in the present specification and claims, the term "purse" includes billfolds, pocketbooks, wallets and the like.

UNITED STATES PATENT OFFICE

2,580,296

LOSS-PREVENTING DEVICE FOR PURSES

Eldon C. Henderson, Paso Robles, Calif.

Application November 12, 1948, Serial No. 59,549

4 Claims. (Cl. 150—47)

1

This invention relates to protective devices for preventing loss of purses from pockets of articles of clothing, such as trouser pockets, and is particularly concerned with a simple, practical and inexpensive device which may be removably engaged with a purse. As used in the present specification and claims, the term "purse" includes billfolds, pocketbooks, wallets and the like.

Various mechanical safety attachments for billfolds, pocketbooks and the like have been proposed heretofore, but have for various reasons not gained wide acceptance. Devices having wire frames or pivoted rigid arms mounted on the purse to swing outwardly from the side edges of the purse after it has been inserted into the pocket for engaging the pocket lining and thereby preventing extraction through the pocket opening are often complicated, or tend to wear out the pocket lining at the point of contact, or distend the pocket to the extent of deforming the clothing and detracting from the neat appearance thereof, or cause discomfort to the wearer, or are apt to get out of order, or suffer from more than one of these drawbacks. Some of the known safety devices of the above mentioned types, as well as other types employing clamps or grips which engage the clothing are time-consuming in that the purse cannot be rapidly inserted into or extracted from the pocket.

It is, therefore, an object of this invention to provide an improved loss-preventing device for securing a purse within the pocket of an article of clothing which device is structurally simple and has as few mechanical elements as possible, and causes no personal discomfort in its use.

It is a further object to provide security against accidental loss and unauthorized removal of a purse from a pocket by means of a guard tab which is secured to the purse by hinge means, the guard tab being extremely simple in operation and installation and being so constructed as to avoid the danger of wearing out or distending the pocket lining or the tendency to distend the clothing to the extent of being noticeable to the eye.

Another object is to provide a loss-preventing device which is independent from the purse or billfold and which may be readily engaged with a purse for securing the latter with a pocket of an article of clothing.

Other objects are to provide means for securing a purse against loss from a pocket which adds but little bulk to the purse; wherein the added guard tab may be utilized for indicia, such as identification and/or advertising; and which can be manufactured at an extremely low cost.

10 The present invention is a loss-preventing device for securing a purse within a pocket of an article of clothing, the device comprising a guard tab made of thin, stiff sheet material, supported at the side edge of the purse, i. e., at the edge which is perpendicular to the pocket opening when the purse is in its normal position within the pocket.

15 In the usual case the pocket opening is substantially horizontal and the said side edge of the purse is vertical. The hinge is constructed to operate on a hinge line which is parallel to said side edge of the purse and is fixed to the guard tab, i. e., immovably connected thereto, either permanently or detachably. The hinge is, further, fixed to a stiff, purse-engaging tab which 20 may be engaged in any suitable manner to the purse. The guard tab is of such width (measured in a direction perpendicular to the hinge line, i. e., horizontally in the usual case) that when it is in its operative, unfolded position (extending away from the purse) the aggregate width of the guard tab, of the stiff structure secured to the hinge, and of the hinge itself exceed slightly the width of the mouth or opening of the pocket, thereby preventing extraction thereof through said mouth or opening. By folding the guard tab about the hinge such aggregate width may be reduced, thereby permitting passage of the purse and guard tab through the pocket opening.

25 In the preferred embodiment of the invention the hinge is made of flexible material, such as fabric, imitation leather (Leatherette), leather, oilcloth, flexible plastic sheet material, etc., and is so secured to the guard tab as to maintain it in spaced relation to the stiff structure to which the hinge is fixed to facilitate folding of the guard tab over the outer face of the purse and substantially parallel to such face when the guard tab is moved to its inoperative position to permit passage of the purse through the pocket opening. The size of the interval between the stiff guard tab and the stiff structure on the other side of the hinge will, of course, depend upon the thickness of the purse. The hinge of flexible material is preferably, but not necessarily, constructed so as to have a natural tendency to unfold the guard tab to its operative position, thereby facilitating use and making it possible to secure the purse within the pocket without the need to grasp the guard tab at its edge when folded alongside of the purse and then fold it outwards with the end of the finger—always an awkward and time-consuming operation. With this preferred construction the guard tab, when released, tends to unfold, but is usually prevented from moving fully to its operative position by en-

gagement thereof with the pocket lining; it is merely necessary to distend the lining momentarily, permitting the guard tab to complete its movement to operative position.

The width of the guard tab is, in the preferred form, somewhat less than the width of the purse-engaging tab, thereby facilitating movement of the guard tab about its hinge while within the pocket.

The invention will be better understood by reference to the accompanying drawing forming a part of this specification and showing one preferred embodiment of the invention by way of illustration. In the drawing:

Fig. 1 is an elevational view of a loss-preventing device of the independent type, shown in its unfolded or operative position;

Fig. 2 is an elevational view, on a reduced scale, of a purse to which the device of Fig. 1 has been applied and which is secured within a pocket, the pocket lining being shown in section;

Fig. 3 is a horizontal sectional view taken on line 3—3 of Fig. 2; and

Fig. 4 is a horizontal sectional view corresponding to Fig. 3 but showing the guard tab in its inoperative position, folded back against the outside of the purse for permitting passage through the pocket opening.

Referring to Fig. 1, the loss-preventing device comprises a guard tab 10, a purse-engaging tab 11, and a connecting hinge 12. The two tabs are made of any thin, relatively stiff sheet material, such as pressed fiber board, celluloid, plastic sheeting, metal, or heavy and surface-coated cardboard. The hinge may be made of any construction permitting repeated flexure, and preferably such as to urge the two tabs into relatively extended positions, as shown. The preferred construction shown comprises imitation leather stitched both to the guard tab and to the purse-engaging tab. Either or both of the tabs may be covered for protection against wear, to present a richer appearance, and to reduce wear of the pocket lining at the point of contact. The last of these purposes is particularly applicable to the guard tab, and in the embodiment shown the hinge and cover are made of one piece of material. Thus, the guard tab is built up of a thin sheet of stiff material 13 completely enclosed in the imitation leather cover 14 which is folded over the upper, straight edge and stitched along the outer and lower edges 15 and 16, the stitches being indicated at 17. Two parallel portions of the cover extend beyond the left edge of the sheet 13, and the tab 11 is secured between them by stitching 18. It will be noted that the near edges of the tab 11 and the stiff sheet 13 are spaced apart by the hinge, leaving an interval the purpose of which will become apparent hereafter. By using two parallel sheets of flexible material spaced apart slightly, the hinge has a tendency to urge the guard tab to its operative, unfolded position.

The width of the loss-preventing device, from the outer edge 15 to the edge 19 of the tab 11, which edge is remote from the hinge 12, is slightly greater than the width of the mouth or opening of the pocket of the clothing within which the purse is to be secured, e. g., a hip trouser pocket. The width of the purse-engaging tab 11 is approximately equal to or slightly less than the width of the purse, while the width of the guard tab is somewhat less than that of the purse-engaging tab. Moreover, it is preferred to cut away the lower, outer corner of the guard tab and to round it as shown at 20, to merge smoothly with the

lower edge 16, which is shorter than the upper edge 21. Making the lower edge shorter than the upper edge obviates the tendency of the lower outer corner of the guard tab to bind against the pocket lining, while the rounded shape prevents wear of the lining at the point of contact with the guard tab. When used to secure a purse in the rear hip pocket the device is positioned with the guard tab toward the center of the body and the hinge vertical; the rounded construction shown then assists in avoiding discomfort to the wearer and in preventing deformation or disarrangement of the clothing which would detract from the neat appearance thereof. The lower corner of the tab 11 may be similarly clipped, as shown at 22. To insure positive engaging action with the top of the pocket lining at the pocket opening for preventing accidental or unauthorized extraction the upper edge 21 of the guard tab is preferably made straight.

In using the device the purse-engaging tab 11 is inserted into a purse of any suitable type into any engaging part thereof, e. g., into a compartment which opens to one of its side edges, or into loops especially provided for the purpose, etc. In the example illustrated in Figs. 2-4, the purse is shown as a billfold 23 of the type that is folded along a transverse axis. The loss-preventing device is attached by placing the tab 11 between the opposed sections with the folded edge 24 of the billfold at the bottom. To insert the billfold into the rear left hip trouser pocket shown, the guard tab is folded over the outer face of the billfold, as shown in Fig. 4, such folding being possible because of the interval between the edges of the stiff sheets 11 and 13. The assembled purse and loss-preventing device are then grasped in folded position and lowered through the opening 25 of the pocket, with the hinge vertical. The guard tab is then released and the lining 26 is moved away from the purse for a small distance, permitting the guard tab to rotate outwardly and to the operative position shown in Figs. 2 and 3. The billfold usually assumes a position at the center of the pocket, causing the tab 11 to project out toward the left as shown, although this will not occur with purses which are not open at both side edges. In the billfold shown, wherein the side edges 27 and 28 of the billfold are open, the outer edges of the tabs 10 and 11 are free to engage the lining 26; but since the lining is usually tailored with sufficient width, both edges do not normally engage the lining.

Because the loss-preventing device is of fixed width and does not resiliently bear against the pocket lining, the tendency to wear the lining is minimized. Various changes may be made in the form of the invention herein shown and described without departing from the spirit of the invention and the scope of the following claims.

I claim as my invention:

1. A loss-preventing device for securing a purse within a pocket of an article of clothing comprising a purse-engaging tab and a guard tab, both tabs being of thin, stiff sheet material, a flexible wear-resistant cover permanently fixed on each face of the guard tab and extending as two parallel sheets beyond one edge of the guard tab and fixed to opposite faces of the purse-engaging tab to form a hinge between said tabs, there being a small interval between the tabs, the combined widths of said tabs and of said interval in a direction perpendicular to the hinge being slightly greater than the width of the opening of said pocket to prevent extraction thereof through

said opening when the tabs are unfolded within the pocket with the hinge substantially perpendicular to the opening, said interval being great enough to permit the guard tab to be folded over the outside face of the purse when the purse-engaging tab is inserted into said purse to permit passage of the purse and loss-preventing device through said opening.

2. A loss-preventing device for securing a purse within a pocket of an article of clothing comprising a purse-engaging tab and a guard tab spaced apart to provide an interval, both tabs being of thin, stiff sheet material, and a hinge of flexible sheet material spanning said interval and fixed to each of said tabs to allow the guard tab to be folded over the outer face of the purse when the purse-engaging tab is inserted into said purse, the aggregate width of the device in a direction perpendicular to the hinge between remote edges being slightly greater than the width of the opening of said pocket to prevent extraction thereof through said opening when the tabs are unfolded within the pocket with the hinge substantially perpendicular to said opening and both tabs having widths less than the width of said opening, whereby the device can be extracted through said opening when the guard tab is folded over the side of the purse.

3. The loss-preventing device according to claim 2 wherein the hinge comprises two sheets of flexible sheet material fixed to opposite faces of the guard tab and to opposite faces of said purse-engaging tab.

4. In combination with a purse adapted to be placed in the pocket of an article of clothing with the side edges of said purse substantially perpendicular to the opening of said pocket; a guard

tab of thin, stiff sheet material extending beyond one of said side edges and having a margin substantially parallel to said edge and spaced therefrom to provide an interval, the width of said guard tab from said margin to the edge remote therefrom being less than the width of the purse; a hinge made of flexible sheet material operable on a hinge line that is substantially parallel to said edge spanning said interval and attached directly to said guard tab and extending beyond said margin thereof; and a purse-engaging tab detachably engaged with said purse and permanently fixed to the flexible material of the hinge adapted to position said hinge line immediately beyond said side edge of the purse to permit the guard tab to be folded over the outer face of the purse by flexing the hinge, the distance from said edge of the guard tab which is remote from the said margin to the part of the purse and engaging tab combination farthest from said edge being slightly greater than the width of the said opening of the pocket to prevent extraction of the purse and the extended guard tab through said opening.
